UNITED STATES PATENT OFFICE.

AMOS G. COLE AND WALTER H. FOSTER, OF LEWISTOWN, AND LAWFORD H. FRY, OF YEAGERTOWN, PENNSYLVANIA.

SPRING FITTING AND QUENCHING MACHINE.

1,425,238.

Specification of Letters Patent. Patented Aug. 8, 1922.

Application filed January 16, 1922. Serial No. 529,554.

To all whom it may concern:

Be it known that we, AMOS G. COLE and WALTER H. FOSTER, citizens of the United States, and LAWFORD H. FRY, a subject of the King of Great Britain and Ireland and the Isle of Man, residing, respectively, in Lewistown, Mifflin County, Pennsylvania, Lewistown, Mifflin County, Pennsylvania, and Yeagertown, Mifflin County, Pennsylvania, have invented certain Improvements in a Spring Fitting and Quenching Machine, of which the following is a specification.

Our invention relates to certain improvements in apparatus for fitting and quenching spring plates.

One object of our invention is to provide two flexible dies between which the spring plate is placed and means for lowering the dies into a tank of oil, or other fluid.

A further object of the invention is to construct the upper dies so that it can be flexed to a greater or less extent, according to the desired shape of the spring and to design the lower die so that it will conform to the shape of the upper die when the plate is clamped between the two dies.

The invention also relates to certain details, which will be fully described herein-after, reference being had to the accompanying drawings, in which:

Fig. 1 is a sectional view illustrating an apparatus in which two sets of dies are used so that when one set is submerged in the fluid, the other is elevated.

Fig. 2 is a sectional view on the line 2—2, Fig. 1;

Fig. 3 is a sectional view on the line 3—3, Fig. 1, drawn to an enlarged scale;

Fig. 4 is a sectional view on the line 4—4,

Fig. 3;

Fig. 5 is a detached perspective view of the upper die;

Fig. 6 is a detached perspective view of the lower die; and

Fig. 7 is a diagrammatic view showing the flat spring plate on the lower die prior to being shaped by the curved upper die.

Referring to the drawings, 1 is a frame mounted in a foundation 2. Located on a floor 3 is the tank 4 containing the quenching oil, or other fluid. This tank is jacketed in the usual manner. 5, 5 are the carrying frames. One end of a rope 6 is attached to one frame 5 and the other end is attached to the other frame 5. The rope passes around sheaves 7 in the upper por-

tion of the main frame 1. 8 is a cylinder and 9 is a piston rod, the outer end of which is attached to the rope 6 at 10 so that, when fluid under pressure enters one end of the cylinder 8, one carrying frame is lowered and the other is raised, and when fluid is admitted to the other end of the cylinder the position of the two carrying frames is reversed. The carrying frames 65 are guided by a central standard 11 and side standards 12 so that the carrying frames, which are narrow, will enter the tank 4 when lowered.

13 is the lower die connected by links 14 to the lower portion of each carrying frame 5. This die is made as shown in Fig. 6 and consists of a thin plate 15 on which are secured a series of bars 16. The plate 15 is a spring plate and can accommodate itself 75 to the upper die, as shown at 17, being made in a manner similar to the die 13. The upper die has a spring plate 18 and a series of cross bars 19 similar to the bars 16 of the lower die. Secured to the carrying frame 5 is a central abutment 20, which comes in contact with the central portion of the upper die. The outer ends of the upper die are connected by links 21 to a cross head 22 adapted to guideways 23 in 85 the frame 5 and an adjusting screw 26 is threaded through this cross head and has its lower bearing in the abutment 20 and its upper bearing in a head 27 mounted in the frame 5. This screw has a hand wheel 28 90 by which it is turned so as to bend the upper die to any degree desired. Carried by the frame is a perforated plate 29, which is located at one side of the dies in order to guide the upper die when it is raised and 95 lowered.

The head 27 is connected to the abutment 20 by plates 30 forming a movable member, which carries the upper die. This movable member slides vertically in the frame and is 100 attached to a cross head 31 by studs 32. This cross head is secured to the lower end of a piston rod 33, which extends into a cylinder 34 secured to the upper end of the frame 5. The piston on this cross head fits 105 the cylinder. Fluid, under pressure, can be admitted to either end of this cylinder so as to raise or lower the parts which carry the upper die.

The operation is as follows: The upper 110 die is raised by fluid under pressure in the cylinder 34 and the die is adjusted to any

degree desired to bend the plate more or less. This is accomplished by turning the hand wheel 28. The lower die assumes a position, as shown in Fig. 7, being substantially flat so that the flat blank *a* can be placed thereon and when in position the upper die is lowered and the continued movement bends the spring blank *a* so that the two will conform to the curve of the upper die. When the spring blank is firmly clamped between the two dies, then fluid is admitted to the cylinder 8 and the entire carrying frame 5 is lowered until the two dies, with the spring blank between them, are submerged in the oil in the tank 4, the other carrier being raised and being in position so that the spring blank clamped therein can be released and another placed in position when the above operation is repeated.

20 We claim:

1. The combination in a machine for fitting springs prior to quenching, of two flexible dies; and means for flexing one of said dies and for holding it in the flexed position, the other die, when one die is moved towards the other with the blank between them, conforming to the shape of the flexed die.
2. The combination in apparatus for fitting and quenching springs, of a flexible upper die; means for flexing said die; a flexible lower die; and means for moving the two dies together with a blank between them so that the blank and the lower die will accommodate themselves to the upper die.
3. The combination in apparatus for fitting and quenching springs, of a tank; a fixed frame; a carrying frame movable on the fixed frame; flexible upper and lower dies between which the spring blank is clamped; means for adjusting the upper die to the lower die; means for bending the upper die to the degree desired so that when the upper die is moved towards the lower die, the lower die and the blank will conform to the shape of the upper die; and means for lowering the carrying frame into the fluid in the tank.
4. The combination in apparatus for fitting and quenching spring plates, of a tank; a carrying frame; a flexible lower die carried by the frame; a flexible upper die; a cross head carrying said upper die; means

on the crosshead for bending the upper die; and means for moving the upper die towards and from the lower die, the lower die, with the spring plate, accommodating itself to the bend of the upper die.

5. The combination of a tank; a carrying frame; a flexible lower die; links connecting the lower die to the frame; a flexible upper die located in line with the lower die; a frame; an abutment secured to the frame and bearing against the center of the upper die; links connected to the outer ends of the upper die; a crosshead connected to the links; a screw for adjusting the crosshead; means for raising and lowering the upper die so that a spring plate can be clamped between the upper and lower dies, the lower die and the spring plate conforming to the shape of the upper die; and means for lowering the carrying frame to allow the carrying frame to enter the fluid in the tank. 75

6. The combination in apparatus for fitting and quenching spring plates, of two flexible dies, each being made of a spring plate having a series of spaced cross bars; and means for flexing one of said plates and holding it in the flexed position, the other plate with the spring blank conforming to the shape of the flexed plate when pressure is applied.

7. The combination in apparatus for fitting and quenching spring plates, of a tank; a carrying frame arranged to be lowered into the tank; a flexible lower die and a flexible upper die between which the spring plate is clamped; means for flexing the upper die and holding it in the flexed position; and means for moving the upper die towards and from the lower die so that when the blank is placed between the two dies and the upper die is moved towards the lower die, the blank and the lower die will be flexed to conform to the shape of the upper die. 95

8. A die for a spring fitting and quenching machine, said die consisting of a metallic plate of spring metal having a series of transverse ribs thereon spaced apart which come in contact with the spring blank to be bent. 100
